UNITED STATES PATENT OFFICE.

ORANGE M. HOWARD, OF SPENCER, INDIANA.

PLATEN PRINTING-MACHINE.

SPECIFICATION forming part of Letters Patent No. 355,171, dated December 28, 1886.

Application filed May 8, 1886. Serial No. 201,585. (Model.)

To all whom it may concern:

Be it known that I, ORANGE M. HOWARD, a citizen of the United States, and a resident of Spencer, in the county of Owen and State of Indiana, have invented certain new and useful Improvements in Platen Printing-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved printing-press, showing it adapted to be operated by hand-power. Fig. 2 is a view of the opposite side of the press, showing the impression being taken. Fig. 3 is a top view of the press, showing the platen resting over the bed. Fig. 4 is a similar view showing the platen raised and broken away at the arms. Fig. 5 is a longitudinal vertical sectional view of the press. Fig. 6 is a perspective detail view of the grippers and of the arms carrying them; and Fig. 7 is a side view of the press, adapted to be operated by any suitable power.

Similar letters of reference indicate corresponding parts in all the figures.

My invention has relation to that class of printing-presses in which the platen is secured to arms pivoted at their ends, and having means for rocking the platen so as to bring it to bear against the type upon the bed and to remove it from it; and it consists in the improved construction and combination of parts of such a press having a horizontal bed, and having the platen secured upon pivoted arms having their fulcra at one end of the bed-frame, and means for drawing the platen down upon the bed and for raising it from the bed, and having means for carrying the sheets over the bed and for carrying them back to a fly, as hereinafter more fully described and claimed.

In the accompanying drawings, the letters A A indicate the side pieces of the frame, which side pieces are of any desired shape and supported in any suitable manner, being preferably made open, for the purpose of decreasing the weight of the entire press. The upper horizontal edges of the side pieces are formed with raised horizontal portions B B,

and the bed C is secured between the upper edges of the side pieces, flush with the upper edge of the same, and extending the length of the raised portions of the edges.

A main shaft, D, is journaled with its ends in bearings E E in the side pieces, near the middles of the lower portions of the side pieces, and the outer ends of this rock-shaft have two upwardly-extending arms, F F, secured to them, one of the said arms being provided with a handle, G, whereby it may be manipulated. The rock-shaft is provided upon its inner portion, inside of the bearings, with arms H H, projecting upward, and rods I I are pivoted to the upper ends of these arms and slide adjustably in perforations in heads K, pivoted to the ends of the levers L, to the curved upper ends of which the platen M is secured. These levers are fulcrumed upon a transverse rod or shaft, N, secured in the side pieces near the upper corners, the rod passing through the levers near their lower ends, and the arms are curved in such a manner that the platen will be brought to bear against the form placed upon the bed when the curved levers are tilted by the arms upon the rock-shaft.

The upper portions of the arms F F upon the ends of the rock-shaft are grooved longitudinally upon the inner sides, and boxes or bearings O O slide in these grooves P, having springs Q secured to their lower ends and to the lower ends of the grooves, for the purpose of drawing the bearings downward, and the shaft R of the grippers S has its ends secured in the bearings, and has rollers T T journaled upon its ends and traveling upon the raised portions of the upper edges of the side pieces.

The gripper-plate U is fixedly secured to the shaft, and the grippers are journaled with their inner ends upon the shaft and have a spiral spring, V, secured to them and to the shaft, forcing them down against the plate.

The ends of the bar W, which connect the inner ends of the grippers, are formed into cranks X X, having a slight downward inclination when the grippers are held closed against the plate. Wedge-shaped lugs Y Y project from the inner sides of the raised portions of the side pieces, so that when the rock-ing arms are operated, and the gripper-shaft

with them, the said cranks will be engaged by the points of the wedge-shaped lugs and be tilted downward by the inclined lower sides of the lugs, raising the grippers and allowing them to release one sheet of paper and to receive another sheet, whereupon they will close again, the cranks slipping off from the rear ends of the lugs in one direction and sliding over them in the opposite direction.

10 Bands or strips of metal Z, preferably of steel or similar flexible metal, are secured at their ends to the edge of the gripper-plate and to a roller, A', journaled with its ends in the side pieces at the rear edge of the bed. These 15 bands are wound upon the roller by means of the weights C', attached to the lower ends of the cords or bands B', which are secured to and wound upon the roller, the band Z being wound upon the roller as the cords B' are unwound 20 from it.

15 A fly, D', has its shaft journaled in the side pieces, and has its slats or teeth projecting toward the roller when raised, and the slotted end of a connecting-rod, E', slides with its 25 longitudinal slot F' upon a bolt, G', upon the fly-shaft, and has its forward end pivoted to the arm H upon the rock-shaft.

20 The inking-rollers H' are journaled with their ends in brackets I', projecting from the 30 bearings for the gripper-shaft, and are provided with guide-rollers J' J' upon their ends, traveling upon the raised portions of the side pieces, and the fountain-roller K' is journaled in the side pieces of the bed, revolving in the 35 fountain L', which is supported below it, so that the inking-rollers may come in contact with the fountain-roller when they arrive at that portion of the machine.

30 One end of the fountain-roller is provided 40 with a ratchet-wheel, M'; and a pawl, N', upon one of the curved platen-arms, engages this ratchet-wheel, and will serve to move it forward for the space of one tooth at each tilt of the platen-arms.

45 The platen is provided with two laterally-projecting lugs, O' O', at the middle of its side edges, the said lugs being preferably the projecting ends of a transverse rod or bar secured across the upper side of the platen, and these 50 lugs may be engaged by the upper hooked ends, P' P', of two arms, Q' Q'. One of these arms is pivoted at its lower end to the shorter arm of a lever, R', and the other one to one end of a disk or arm, S', said lever and arm being secured to the opposite ends of the rock-shaft T', journaled in bearings in the side pieces 55 of the frame.

60 The arms Q' Q' have connecting-rods U' U', pivoted to them near their middle and to the 65 arms F F, carrying the grippers and inking-rollers, and the upper ends of the arms Q' Q', near the hooked ends, are provided with forwardly-projecting and upwardly-inclined lugs V' V', the forward ends of which project beyond the ends of the hooks and serve to receive the laterally-projecting lugs of the platen, 70 guiding them into the hooks and gradually

letting the platen down, preventing it from dropping upon the form upon the bed and injuring the type; and it will be seen that when 70 the platen is tilted down and has been engaged by the hooks the lever R' is raised, which operates the shaft T' and the disk S', thus drawing the arms Q' Q' downward and causing the platen to press against the form and to take 75 the impression.

The arms carrying the grippers and the inking-rollers are preferably bulged out about their middles, as shown at W', for the purpose of allowing them to be drawn over the inner 80 or lower ends of the arms and the lever upon the rocking shaft.

One end of the frame is provided with an inclined table, X', from which the sheets to be fed into the press are taken, the sheets resting 85 upon the table.

When the press is to be driven by power applied to a revolving shaft, the drive-shaft Y' is journaled in the end of the machine below the feed-table, having a wheel, Z', to which the revolving motion may be imparted by any suitable means, and this shaft is provided with a pinion, A'', which meshes with a cog-wheel, B'', to the face of which a pitman, C'', is pivoted, which pitman is pivoted at its forward 95 end to one of the arms carrying the grippers and inking-rollers, or two pitmen are pivoted at both ends of the shaft carrying the cog-wheel, and are pivoted to both arms. The impression-hooks are operated by means of a 100 pitman secured at one end to an eccentric upon the shaft Y'' and at the other to the lever R'. 95

It will be seen that when the form is in place upon the bed and the lower face of the platen has been prepared to make an even impression from the form, the paper may be fed to the grippers, which will be opened when their arms are tilted back, the cranks engaging the wedge-shaped lugs, and upon being tilted forward the arms will carry the grippers 110 forward, which have in the meantime been closed by their spring, the crank being released, and the grippers will draw the sheet of paper with them, the sheet resting upon the bands secured to the gripper-plate and 115 winding upon the roller, the said bands in unwinding winding the weighted bands upon the roller and raising the weight. The platen will be drawn over the bed by the time the sheet has been carried over the bed and form 120 and the inclined lugs upon the hooked arms have received the lugs of the platen, breaking the force of its fall and guiding the lugs into the hooks, whereupon the hooked arms may be drawn down, drawing the platen down with 125 them and making the impression. The stroke or tilt of the platen may be adjusted by adjusting the rods, connecting its lower arms to the arms upon the rock-shaft in the heads pivoted to the lower ends of the platen-arms; and the 130 force of the impression may be regulated in the press, when it is driven by rotary power, by adjusting the length of the connecting-rod between the gripper-carrying arm and the le-

125

ver. The sheet will travel upon the bands when the impression has been made and when the gripper-arms are tilted, the bands carrying the sheet over the ends of the arms of the fly, which will be tilted at the latter part of the tilt of the gripper-carrying arms, placing the sheet upon its pile, in the usual manner.

The entire press may be made very light in proportion to the power which it will develop, as the platen will be re-enforced by the ends of the arms extending over the ends of the platen and by the transverse bar or rod extending across the platen, upon which rod the pressure in making the impression will be exerted, and the bed may be made comparatively light, with diagonal ribs or similar re-enforcing means, and the frame may be made open and light, so that the machine may be comparatively light, there being but very few moving parts in the press.

The feeding and delivery of the sheets upon the bed and form being automatic, the machine may print a comparatively large number of impressions in a given time, as the press may be run as fast as the sheets may be fed to the grippers and the platen may be tilted and depressed.

The press may be made of any size, and may be employed for any kind of printing, being on account of its lightness and simplicity especially adapted for job-printing or similar light printing.

Having thus described my invention, I claim and desire to secure by Letters Patent of the

United States—

1. In a printing-press, the combination of a horizontal bed, two levers pivoted at one end of the press, a platen secured to the curved upper ends of said levers and heads pivoted to the lower ends, a shaft journaled under the bed and having upwardly-projecting arms and means for rocking it, and rods pivoted to the upper ends of the said arms and secured adjustably in the heads pivoted to the lower ends of the curved levers, as and for the purpose shown and set forth.

2. In a printing-press, the combination of a horizontal bed, a set of grippers, bands secured to them, a roller having the ends of the bands secured to it, and a platen secured upon curved arms pivoted at one end of the machine, and means, substantially as described, for operating said roller and said platen, as and for the purpose shown and set forth.

3. In a printing-press, the combination of two side pieces having horizontal upper edges and having raised portions upon the said upper edges, a horizontal bed placed between the side pieces flush with their upper edges and at the raised edges of the same, a rock-shaft having arms at its ends formed with longitudinal grooves upon their inner sides, bearings sliding in the said grooves and having springs drawing them downward, a shaft secured in the bearings and having grippers provided with means for opening them at one end of the bed and having rollers at its ends traveling

upon the raised portions of the edges of the frame-pieces, a roller journaled parallel to one end of the bed and having cords wound around it, provided with a weight at their other ends, being secured to the roller at the inner ends, bands secured to the grippers and to the roller upon which they are wound, and a platen having means for tilting it over the bed when the grooved arms are tilted forward and for raising it when the arms are tilted back, as and for the purpose shown and set forth.

4. In a printing-press, the combination of a horizontal bed, a set of grippers having means, substantially as described, for carrying them over the bed forward and back and having carrying-bands secured to them, an ink-fountain at one end of the bed having a revolving roller, a pair of inking-rollers journaled parallel with the grippers, forward of them, and a platen having means for tilting it over the bed and away from it, as and for the purpose shown and set forth.

5. In a printing-press, the combination of a horizontal bed, a platen secured to curved levers pivoted near one end of the bed and hooked arms engaging lugs projecting from the sides of the platen, and means, substantially as described, for drawing said arms downward, as and for the purpose shown and set forth.

6. In a printing-press, the combination of a horizontal bed, a platen having laterally-projecting lugs at the middles of its side edges, a rock-shaft journaled below the bed and having a lever at one end and an eccentric disk or arm at the other end, and hooked arms pivoted at the lower ends to the inner end of the lever and to the disk or arm and engaging the lugs upon the platen with their hooked upper ends, as and for the purpose shown and set forth.

7. In a printing-press, the combination of a platen having laterally-projecting lugs upon its side edges, with arms having hooked upper ends and having forwardly and upwardly projecting inclined lugs below the hooks, longer than the hooks, and having means, substantially as described, for drawing the said arms downward and for tilting them, as and for the purpose shown and set forth.

8. In a printing-press, the combination of a horizontal bed, a platen having means for tilting it forward and back over the bed and having laterally-projecting lugs upon its side edges, levers having the fulcrum below the bed, a rock-shaft journaled below the bed and having hooked arms pivoted eccentrically at the ends of the same engaging the lugs of the platen, a lever secured to the shaft, and connecting-rods pivoted to the rocking arms and to the hooked arms, as and for the purpose shown and set forth.

9. In a printing-press, the combination of a horizontal bed, a set of grippers, a roller journaled at one end of the bed, bands secured to the grippers and to the roller winding upon it, bands secured to the roller and winding

upon it in opposite direction to the other bands and having weights attached to their free ends, and a fly having the upper ends of its arms bearing against the roller, as and for the purpose shown and set forth.

10. In a printing-press, the combination of a horizontal bed, a rock shaft journaled below the bed and having two arms at its outer ends and two upwardly-projecting arms inside of its bearings, a platen secured to the curved upper ends of two levers pivoted near the lower ends at a distance from one end of the bed, connecting-rods pivoted to the upper ends of the upwardly-projecting rock-arms 15 and to the lower ends of the platen-arms, a set of grippers secured at the upper ends of the arms, at the outer ends of the rock-shaft, and having means for opening them at one end of the bed, a roller at that end of the bed 20 having cords wound around it and provided with weights at their free ends, bands secured to the set of grippers and to the roller winding upon it in the opposite direction to the weighted bands, a fly journaled below the 25 roller to the rear of the same and having the ends of its arms or fingers bearing against the rear side of the roller, and a connecting-rod

having a longitudinally-slotted head sliding upon a bolt upon the end of the fly-shaft, and having its forward end pivoted to one of the 30 rock-arms, as and for the purpose shown and set forth.

11. In a printing-press, the combination of a horizontal bed having diagonal ribs upon its under side, with a platen having the forwardly-curved ends of a pair of arms secured across the ends, and having the arms pivoted near the lower ends at a distance from one side of the bed, having means for rocking the arms, and having a transverse bar bearing with 35 its ends over the ends of the arms and projecting beyond the ends of the platen, and arms having hooked upper ends engaging the ends of the bar and having means for depressing them, as and for the purpose shown and 40 set forth.

In testimony that I claim the foregoing as my own I have hereunto affixed my signature in presence of two witnesses.

ORANGE M. HOWARD.
